STEAM GENERATOR

George H. Daniels, Westfield, N. J., assignor to
 The Babcock & Wilcox Company, Newark, N. J.,
 a corporation of New Jersey

Application September 7, 1938, Serial No. 228,747

2 Claims. (Cl. 122—473)

The present invention relates to the construction and operation of steam generating units, and more particularly, to water tube steam boilers particularly designed for and especially useful in marine installations.

Steam generating installations in the marine field are characterized by relative low space, weight, headroom and other limitations, all contributing towards an extremely compact light-weight generator design without sacrifice of efficiency requiring a minimum of special construction of the surrounding ship structure. The recent trend in this field towards units adapted to generate high pressure high temperature steam with relatively high superheat temperatures controllable over a wide range, even to zero superheat, has substantially increased the problems of design and construction. One such unit involves the use of a separately fired auxiliary furnace chamber in the same setting for regulably heating the steam superheating surface. To reduce the space requirements of the unit and ship adaptation to it, and to more effectively utilize the heating gases from the auxiliary furnace, the setting is provided with only a single gas outlet flue arranged to receive all of the heating gases from both the main and auxiliary furnace chambers. While this construction tends to increase the amount of heat absorbed from the heating gases from the auxiliary furnace due to their contact with heat absorbing surface subsequent to passing through the main furnace chamber, the continuous flow of products of combustion from the auxiliary furnace through the main furnace chamber tends to interfere with the combustion in the main furnace chamber due to the consequent introduction of a substantial amount of relatively cold inert gases therein.

The main object of my invention is the provision of an improved construction of a steam generating unit of the general type described which is particularly characterized by its compactness, effective superheat control over a wide range, advantageous combustion conditions in both the main and auxiliary furnaces, and high overall efficiency.

The various features of novelty which characterize my invention are pointed out with particularity in the claims annexed to and forming a part of this specification. For a better understanding of the invention, its operating advantages and specific objects attained by its use, reference should be had to the accompanying drawing and descriptive matter in which I have

10 illustrated and described a preferred embodiment of my invention.

Of the drawing:

Fig. 1 is a partly diagrammatic sectional elevation of a steam generating unit constructed 15 in accordance with my invention; and

Fig. 2 is a section taken on the line 2—2 of Fig. 1.

The steam generating unit illustrated comprises a setting 10 enclosing a relatively wide bank of inclined steam generating tubes 11 extending between a lower water drum 12 and an upper steam and water drum 13 laterally offset from and of substantially larger diameter than the drum 12. At the opposite side of the setting is arranged a bank of inclined steam generating tubes 14 extending between the drum 13 and a lower water drum 15. The tube banks 11 and 14 define therebetween an A-shaped space closed at its ends by the vertical end walls of the setting, and extending downwardly to a refractory bottom pan 16 below the level of the drums 12 and 15. The setting is provided with a single heating gas outlet flue 17 at the outer side of the tube bank 11, i. e. the side opposite the A-shaped space, and adjacent to the steam and water drum 13. A bank of economizer or air heater tubes 18 is positioned in the outlet flue 17.

In accordance with my invention the tube bank 14 is divided into three spaced groups of water tubes 14^a, 14^b, and 14^c. The group 14^a contains only a relatively few rows of tubes at the inner side of the bank and serves as a water screen for a superheater hereinafter described. The tubes 14^b are of larger diameter than the tubes 14^a or 14^c, and are arranged in a single row intermediate those groups. The tubes 14^b also serve as supports for an inclined bank of U-shaped steam superheating tubes 20 extending transversely of the tube bank 14 in the lower portion of the space between the tube groups 14^a and 14^c. The ends of the U-shaped superheater tubes 20 are connected to external inclined headers 21 and 22, with the header 21 arranged to receive saturated steam from the steam and water drum 13 through pipes 23. The tubes 14^b are of somewhat L-shape, and arranged to extend along and support the corresponding side wall of the setting 10. The tube group 14^c also has only a few rows and is arranged with the longer legs of the tubes substantially spaced from the superheater tubes 20.

The A-shaped space between the tube banks 11 and 14 serves as the combustion space of the unit, and is preferably divided into a main fur-

nace chamber 25 and an auxiliary furnace chamber 26 by a row of tubes 27 extending from a header 28 to the drum 13. The header 28 is arranged along the bottom 16 below the steam and water drum 13 and connected by supply tubes 29 to the drum 15. The tubes 27 are bent laterally at an intermediate point towards the tubes 14^a and extend upwardly along the inner side of the same from a point adjacent the upper end of superheater tubes 20. The tubes 27 are fully studded, as shown in Fig. 2, for a portion of their length and the studs covered and intertube spaces closed with refractory material 30 to form a fluid cooled partition 31 extending upwardly from the header 28 to the tube bank 14 at a point adjacent the upper end of the superheater. A metallic baffle 32 extends laterally from the upper end of the partition across the tubes 14^a and 14^b along the upper end of the superheater tube group, terminating at the outer side of the superheater. The main furnace chamber 25 is fired by a group of fluid fuel burners 35 arranged to discharge longitudinally thereof through corresponding burner ports 36 located in one of the end walls of the setting. The auxiliary furnace chamber 26 is fired by similarly arranged independently operable fluid fuel burners 37 through burner ports 38. The burners 37 can be operated as desired to control the superheat temperatures over a relatively wide range, either automatically or manually, suitable automatic mechanism for this purpose being well known. As an alternative the boiler can be operated to produce saturated steam and without superheating it by using the main furnace chamber 25, and not using the auxiliary furnace chamber 26.

With the described construction the steam generating unit is started up with only main furnace chamber burners 35 in use. The heating gases generated by the fuel burning in suspension flow transversely of the tube bank 11 to the gas outlet flue 17, passing over the economizer tubes 18 before leaving the unit. During the starting-up period the fluid-cooled partition 31 forms an effective radiant heat shield between the main furnace chamber and the auxiliary furnace chamber and its associated parts, particularly the superheater tubes 20. With steam flowing through the superheater tubes, the auxiliary furnace chamber burners 37 are put into operation. The heating gases generated in the auxiliary furnace chamber flow upwardly across the screen tubes 14^a and superheater tubes 26, the flow path in this section being defined by the setting walls, the partition 31, and baffle 32. After leaving the superheater tubes 20 the gases flow around the upper end of the baffle 32 while contacting with the tubes 14^c. The space between the superheater tubes and tubes 14^c serves as a gas flow equalization and turning space, permitting a reversal in direction of the gas flow with a relatively low pressure drop. The gases on rounding the baffle 32 flow across the upper portions of the tubes 14^b, 14^a, and 27. The heating gases from the auxiliary furnace chamber then flow across the upper portion of the main furnace chamber and upper part of the tube bank 11 to the gas outlet flue 17.

The described flow path of the auxiliary furnace gases insures an efficient use of the heat values thereof, and a minimum interference thereby with the combustion conditions in the main furnace chamber. The described steam generating unit with its integrally arranged independently fired superheater furnace and single

gas outlet provides an extremely compact structure having relatively low floor space and head room requirements. The construction and arrangement of the main and auxiliary furnace chambers permits the maintenance therein of combustion conditions contributing to a high thermal efficiency of the unit. The arrangement of the auxiliary furnace chamber and its associated parts insures effective control of superheat conditions over a wide range and with a high upper limit.

While in accordance with the provisions of the statutes I have illustrated and described herein in the best form of the invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. A steam generator comprising a setting, an upper steam and water drum, a pair of spaced lower water drums, a bank of inclined steam generating tubes connecting said upper drum to one of said lower drums, a group of steam generating screen tubes connecting the upper drum to the other of said water drums, a vertically arranged partition arranged to divide the space between said tube bank and said screen tube group into a main furnace chamber and a laterally adjoining auxiliary furnace chamber, the portion of said group of screen tubes extending throughout one side of said auxiliary furnace chamber being unobstructed, means for firing said main furnace chamber, a group of superheater tubes extending along the outer side of said unobstructed portion of said screen tube group and of said auxiliary furnace chamber, means for independently firing said auxiliary furnace chamber, a single heating gas outlet flue at the outer side of said tube bank and arranged to receive all of the heating gases flowing from both of said furnace chambers, said flue being so located that the heating gases from said auxiliary furnace chamber flow over said unobstructed screen tube group portion, superheater tubes and tube bank and across said main furnace chamber before entering said flue, and said partition terminating below said upper drum and arranged to direct the heating gas flow from said auxiliary furnace chamber over said superheater tubes and into the upper part of said main furnace chamber and to shield said superheater tubes from flame radiation from said main furnace chamber.

2. A steam generator comprising a setting, an upper steam and water drum, a pair of spaced lower water drums at substantially the same level, a bank of inclined steam generating tubes connecting said upper drum to one of said lower drums, a group of inclined steam generating screen tubes connecting the upper drum to the other of said water drums, a vertically arranged fluid cooled partition arranged to divide the space between said tube bank and said screen tube group into a main furnace chamber and a laterally adjoining auxiliary furnace chamber, the portion of said group of screen tubes extending throughout one side of said auxiliary furnace chamber being unobstructed, means for firing said main furnace chamber, a group of horizontally arranged superheater tubes extending along the outer side of said unobstructed

portion of said screen tube group and of said auxiliary furnace chamber, means for independently firing said auxiliary furnace chamber, a single heating gas outlet flue at the outer side of said tube bank and arranged to receive all of the heating gases flowing from both of said furnace chambers, said flue being so located that the heating gases from said auxiliary furnace chamber flow over said unobstructed screen tube group portion, superheater tubes and tube bank

5 and across said main furnace chamber before entering said flue, and said fluid-cooled partition terminating below said upper drum and arranged to direct the heating gas flow from said auxiliary furnace chamber over said superheater tubes and into the upper part of said main furnace chamber and to shield said superheater tubes from flame radiation from said main furnace chamber.
